UNITED STATES PATENT OFFICE

2,037,920

STRIP SEAL METAL CONTAINER

William F. Punte, Syracuse, N. Y., assignor to
 Continental Can Company, Inc., New York,
 N. Y., a corporation of New York

Application May 23, 1932, Serial No. 613,094

2 Claims. (Cl. 220—61)

The invention relates to new and useful improvements in metal containers, and more particularly to a metal container wherein the cover is secured to the container body by a sealing strip. 5 An object of the invention is to provide a metal container having a body portion provided with a retaining shoulder and a cover which overlies the body portion engaging an elastic gasket interposed between the cover and the container body, 10 with a sealing strip which underlies said shoulder and overlies the cover, and which securely clamps the cover to the container.

A further object of the invention is to provide a container of the above type wherein the cover has an outside slip engagement with the container body and is provided with an upwardly projecting portion forming a recess for the sealing gasket so that said sealing gasket may extend beyond the side wall of the container body. 15

20 In the drawing—

Figure 1 is a view partly in side elevation and partly in section showing a metal container embodying the improvements;

Fig. 2 is a plan view of a portion of the same;

Fig. 3 is an enlarged vertical section through a container and sealing strip showing the parts assembled and prior to the subjecting of the sealing strip to pressure for sealing the container, and

Fig. 4 is a view similar to Fig. 3, but showing 30 the sealing strip after pressure has been applied for the closing of the container.

The invention is directed to a metal container having a cover provided with a depending flange which slips down over the container body making engagement therewith so that said cover provides a closing means for the container after the sealing strip has been removed. The body wall of the container has an annular depression forming a holding shoulder spaced from and adjacent the upper edge of the body wall. Said body wall terminates in an inturned hollow bead. The cover flange is bent outwardly at the upper portion of the flange and the cover disk is likewise curved upwardly directly above the bead on the container body, so as to provide a recess or channel for the sealing material. The flange terminates adjacent but above the holding shoulder on the container body, and is bent outwardly and inwardly to form a half bead, the inner face of which is in line with the inner face of the flange. The sealing strip has its ends overlapping. Said sealing strip has an inwardly extending portion which underlies the shoulder on the container. It also has an inwardly projecting portion which 55 overlies the cover. The upper face of the cover is

curved outwardly, and the inwardly projecting portion of the sealing strip is also curved initially about a shorter radius, but so that the inner edge thereof extends well over the curved portion on the cover. After the sealing strip has been applied 5 to the container, and the ends of the sealing strip joined, it is then subjected to die pressure in a direction lengthwise of the container wall, which shortens the distance between the inwardly projecting portions of the sealing strip, causing the 10 upper portion thereof to curl inwardly and downwardly into contact with the cover. This pressure applied to the sealing strip also forces the cover into tight sealing contact with the container body, and the sealing strip, when released, holds 15 the cover in sealed engagement with the container body.

Referring more in detail to the drawing, the container consists of a body portion 1 which is preferably cylindrical. A closing bottom end 2 20 is secured to the container body by double-seaming. Said container body is provided at the upper end thereof with an inturned hollow bead 3. At a distance below this hollow bead is an annular depression 4 providing a substantially 25 horizontal holding shoulder 5. This annular depression or necking-in of the body produces a container wherein both ends are of substantially the same diameter, and at the same time the locking shoulder for the retaining ring is provided in the wall of the container. The container is closed by a cover 6 which is in the form of a disk extending across the open end of the container, and a depending flange 7. This flange extends down over the body wall of the container, 35 engaging the same so as to be held thereon by a light frictional grip. This provides a cover which may be used for re-closing the container after the sealing strip is removed. The cover flange is bent outwardly at 8 and the cover disk 40 is curved upwardly at 9 in order to form a channel for the sealing material which is in the form of a sealing ring 10. While a sealing ring is shown, which is pre-formed, the sealing material may be placed on the cover, or a sealing disk 45 extending all the way across the cover may be used. The lower edge of the flange terminates adjacent but above the holding shoulder 5. Said flange is bent outwardly, thence downwardly and inwardly to form a half bead 11, the inner face 50 of which is substantially in line with the inner face of the flange. This bead at the lower end of the flange of the cover serves to place the sharp edge of the cover flange adjacent the body and prevents any danger of cutting the hands when 55

removing the sealing strip. It also forms a substantial support for the sealing strip to rest against when it is pressed into position and maintains the wall of the sealing strip substantially 5 parallel with the upper section of the body wall.

The cover is secured to the container body by a sealing strip which is indicated at 12 in the drawing. Said strip has overlapping ends, one of which is indicated at 13. The upper portion 10 of the sealing strip is bent inwardly at 14 and overlies the cover. This inwardly bent portion is curved upwardly and downwardly and initially about a smaller radius than the curved portion 8 of the cover. It contacts with the curved portion 15 of the cover when applied thereto well beyond the crown of the curved portion 8. The sealing strip 12 is also provided with an inwardly projecting portion 12a at its lower edge which is initially slightly inclined upwardly. This inwardly projecting portion 12a extends underneath the shoulder 5 when the sealing strip is applied to the container.

In Fig. 3 of the drawing, the sealing strip is shown as having been applied to the container 25 after the parts are assembled. It is then subjected to die pressure. One of the dies extends beneath the inturned portion 12a, while the other overlies the inturned portion 14 of the sealing strip. The dies when moved toward each 30 other engage the sealing strip and shorten the sealing strip between the inturned portions 12a and 14 thereof. The dies starting at the inturned portion 12a and continue to curl the portion 14 which results in a shortening of the distance between the inturned portions. This die pressure 35 also forces the cover into very tight sealing contact with the gasket 10, and the gasket into contact with the hollow bead 8. Thus it is that a very tight seal is produced, and the sealing strip, when the die pressure is released, retains the cover in this tight sealed engagement with the container body.

The method of closing the container which includes the steps of de-forming the sealing strip by die pressure which is exerted in a direction lengthwise of the container wall while the sealing strip is restrained against any bulging or detaching movement is described more in detail and claimed in my co-pending application Serial 50 No. 11,852, filed March 19, 1935. When it is desired to open the container and break the seal, the end 13 of the strip is forcibly pulled outwardly and this will disconnect the sealing strip from the container. The cover can then be removed and replaced for re-closing the container at will.

The can body is made in cylindrical form, after which the outer edge is rolled to form a bead. This rolling of the edge produces a severe 60 strain on the lapped portions of the body at the side seam, and sometimes causes the bond to be broken. The fracture does not extend far along the side seam, and by the present construction of cover and sealing band, the sealing material 65 extends well over on to the outer face of the bead and the body wall so as to insure a perfect seal.

It is obvious that minor changes in the details of construction of the metal parts and in the

manner of applying the pressure for deforming the sealing strip and sealing the container may be made without departing from the spirit of the invention as set forth in the appended claims.

Having thus described the invention, what I 5 claim as new and desire to secure by Letters Patent, is—

1. A metal container comprising a body portion having an annular depression in the wall thereof adjacent the upper end forming a holding shoulder, said body wall being rolled inwardly at its upper edge to form a hollow bead, said shoulder being disposed beneath said hollow bead, a cover having a depending flange extending over and engaging the outer face of the wall 10 of the container, said flange terminating adjacent and above said shoulder and being bent outwardly and inwardly to form a half bead at the lower edge of said flange, said cover flange being bent outwardly at the upper portion thereof and adjacent the hollow bead, said outwardly bent portion being of substantially the same diameter as the diameter of the half bead at the lower edge of the flange, said cover having an 15 annular portion above the hollow bead which is curved upwardly, a sealing member located within the cover and extending across the annular portion and into the recess formed in the cover flange, and a sealing strip having inwardly projecting portions, one of which underlies the 20 shoulder on the container body and the other of which overlies the upwardly curved portion of the cover directly above the hollow bead, whereby said sealing strip may be utilized for forcing the cover against the sealing material and the 25 sealing material against the hollow bead on the container body by direct pressure lengthwise of the wall of the container.

2. A metal container comprising a body portion having an annular depression in the wall 40 thereof adjacent the upper end forming a shoulder, said body wall being rolled inwardly at its upper edge to form a hollow bead, said shoulder being displaced beneath the bead, a cover having a depending flange extending over and engaging the outer face of the wall of the container, said flanges terminating adjacent and above the shoulder and being bent outwardly and inwardly to form a half bead at the lower edge 45 of said flange, said cover flange being bent outwardly at the upper portion thereof and of substantially the same diameter as the diameter of the half bead at the lower edge of the flange, said cover having an annular portion above the hollow bead which is curved upwardly, a sealing member located within the cover and over said hollow bead, and a metal sealing strip having inwardly projecting portions, one of which underlies the shoulder of the container body and the other of which overlies the upwardly curved 50 portion of the cover directly above the hollow bead whereby said sealing strip may be utilized for forcing the cover against the sealing material and the sealing material against the hollow bead on the container body by direct pressure lengthwise of the wall of the container and against the upper and lower faces of the metal sealing strip.
